UNITED STATES PATENT OFFICE

2,188,116

GAS BURNER

John Ernest Neale and Albert Guest, Coventry,
EnglandApplication January 23, 1939, Serial No. 252,486
In Great Britain November 24, 1937

2 Claims. (Cl. 158—104)

This invention relates to coal-gas or other gas burners, and particularly to such as are for use in geysers, where a plurality of flames can emanate from different openings.

5 Our main object is to provide a simple and inexpensive but efficient gas burner.

A gas burner, according to the invention, includes a gas-supply pipe with a pin-prick or like small hole therein, and a short tube with diametrically-opposite through holes in it to allow of it being slipped along the pipe and positioned thereon with the pin-prick or like small hole lying substantially in the main axis thereof, the tube being of such size as to leave spaces on opposite sides of the pipe along which air can be drawn to mix with the gas issuing from the small hole and to form therewith a combustible mixture in the interior of the tube, and the tube having its end on that side of the pipe adjacent 20 the small hole shaped as an appropriate outlet opening.

The invention further consists in a multi-jet gas burner including a gas-supply pipe with a series of spaced pin-pricks or like small holes in 25 the face which will be uppermost when the pipe is horizontal and the parts of the burner are properly assembled, the pipe having associated with each small hole a short tube as above specified.

The invention further consists in a multi-jet 30 gas burner including a plurality of spaced gas-supply pipes arranged as specified above.

In the accompanying drawing:

Figure 1 is a perspective view of a multi-jet gas burner, for a geyser, according to the invention; and

Figure 2 is a sectional view thereof.

In the construction shown, use is made of a main gas pipe 11 of relatively large bore to which are connected a plurality of spaced, parallel, 40 transverse gas-supply pipes 12 of smaller bore. Along the upper faces of these pipes 12 are provided at intervals small holes 13, of the size of pin-pricks, through which the gas can issue.

Associated with each of these small holes is a 45 mixing chamber 14 terminating with an outlet opening 15 through which the combustible mixture can issue to be ignited.

The mixture chambers are formed in short tubes 16 of an internal bore just slightly greater 50 than the external diameter of the pipes 12, so that they can be provided with transverse through holes to enable them to be threaded thereon and secured in upright position to coact with the small holes 13, as shown. The small 55 holes lie on the respective axes of the tubes 16.

Air for mixing with the gas issuing through the small holes can be brought in through the lower ends of these short tubes and along opposite sides of the spaced parallel pipes 12. Their upper ends may be flattened as shown to provide appropriate 5 outlet slits through which the combustible mixture issues.

In this way the gas for the individual flames is split up before air is mixed with it, and the resulting small dimensions of each mixture 10 chamber and the small amount of the mixture being dealt with therein effectively prevent the possibility of "blow-back" occurring, whilst in addition it is possible to ensure that the combustible mixture is a very satisfactory one, where- 15 by the burner has a high efficiency.

What we claim as our invention and desire to secure by Letters Patent of the United States is:

1. In a gas burner, a distributor pipe in communication with a source of gas supply and having its axis arranged substantially horizontally with a gas escape orifice in the upper portion of said pipe, and a mixer tube having its axis arranged substantially vertically and being of short vertical length, said mixer tube being of a 25 horizontal diameter appreciably greater than the vertical diameter of said distributor pipe, said mixer tube being composed of lower and upper sections, said lower section being substantially cylindrical in form and having diametrically opposite openings in its side wall of a diameter to fit snugly over said distributor pipe whereby to leave substantial vertically uninterrupted air passages within said lower section at opposite sides of said distributor pipe, said diametric openings of said lower section being spaced above the bottom edge of said section, said upper section of said mixer tube having flat mutually sloping side walls and a burner slit at the upper ends of said flat side walls, the length of said slit extending at substantially right angles to the axis passing through said diametric openings whereby the end portions of said slit will lie in substantially vertical alignment with the vertical air inlet passages in the lower section. 40 45

2. In a gas burner, a distributor pipe in communication with a source of gas supply and having its axis arranged substantially horizontally with a gas escape orifice in the upper portion of said pipe, and a mixer tube having its axis arranged substantially vertically and being of short vertical length, said mixer tube being of a horizontal diameter appreciably greater than the vertical diameter of said distributor pipe, said mixer tube being composed of lower and upper 50 55

sections, said lower section being substantially cylindrical in form and having diametrically opposite openings in its side wall of a diameter to fit snugly over said distributor pipe whereby to leave substantial vertically uninterrupted air passages within said lower section at opposite sides of said distributor pipe, said diametric openings of said lower section being spaced above the bottom edge of said section, said upper section of said mixer tube having flat mutually sloping side walls and a burner slit at the upper ends of said flat side walls, the length of said slit ex-

tending at substantially right angles to the axis passing through said diametric openings whereby the end portions of said slit will lie in substantially vertical alinement with the vertical air inlet passages in the lower section, said inclined flat walls being substantially triangular in form with their apex portions directed downwardly whereby the flat walls extend down very close to the gas orifice and extend gradually out to the end portions of the slit. 5

JOHN ERNEST NEALE.
